UNITED STATES PATENT OFFICE.

CURTIS JOHNSON, OF PRESCOTT, IOWA.

HARNESS ATTACHMENT.

1,157,544.

Specification of Letters Patent.

Patented Oct. 19, 1915.

Application filed May 18, 1915. Serial No. 28,867.

To all whom it may concern:

Be it known that I, CURTIS JOHNSON, a citizen of the United States, residing at Prescott, in the county of Adams and State 5 of Iowa, have invented certain new and useful Improvements in Harness Attachments, of which the following is a specification.

My invention relates to an improvement in harness attachments, and more particularly 10 to the layers used in connecting the breeching to the breeching-stay or hip-straps. These have hitherto been made of leather, and one edge of this leather has been stitched by machinery to the wear leather or safe, 15 and then the other edge required stitching by hand.

The purpose of my present invention is to do away with all this and produce a much 20 cheaper, stronger, and more durable layer composed of sheet-metal that can be made up in less time, and can be riveted to the wear leather or safe instead of being stitched thereto.

In the accompanying drawings:—Figure 25 1 is a view showing the attachment applied to the usual breeching; Fig. 2 is a blank from which the layer is made; Fig. 3 shows it partly completed, with the ends and spurs at the edge partly bent; and Fig. 4 is a section through the entire device after having 30 been riveted to the wear leather or safe. Fig. 5 is a transverse section on an enlarged scale.

The strip or blank A is made of sheet- 35 metal of any length or width to suit requirements. It is provided with a slot 1 at or near one end, and rivet holes 2, 2 at intervals throughout its length, and is cut at the edge to form the spurs 3, 3. The slot 1 is 40 adapted to receive the tongue of the buckle 4, and the buckle is held in place by the end of the strip or blank A being bent around until the rivet-holes at opposite ends of the slot are in registry. The opposite end is 45 bent around in similar fashion to embrace the ring or loop 6 attached to the breeching-strap 7. The strap loops 8, 8, are bent around the edge of the metal, and are fas-

tened by forcing the spurs 3, 3, at the edge of the metal layer therethrough. The spaces 50 between these loops on the lower side of the metal layer may be filled with pieces of leather 9, 9. The wear leather or safe 10 is of the usual form and design, and is fastened rigidly and permanently to the layer by 55 means of rivets 11, 11, extending through the several holes 2, 2, in the metal layer, and the holes 12, 12, in the wear leather or safe. In this way, a very simple, strong, and durable layer is formed, which will wear as long 60 as the most durable part of the harness. Necessarily it can be made much cheaper than the present form of layer which has to be stitched, and then under circumstances of unusual difficulty, and when japanned and 65 finished, it does not look different from the present leather layer, and a casual observer would scarcely detect the difference.

I claim:

A sheet metal layer for harness having 70 rivet holes located at predetermined distances apart along its longitudinal center, provided with an elongated slot between two of the rivet holes at one end of said layer, and constructed with spurs at the edges at 75 points between the rivet holes, in connection with a buckle the tongue of which extends through the slot, the slotted end of the layer inclosing the pintle of the buckle and with the rivet holes at the opposite ends of 80 the slot in registry, the opposite end of said layer inclosing a loop bar, the two rivet holes nearest that end being in registry, strap loops embracing the edges of the layer and fastened thereto by the said spurs, and a 85 wear leather or safe secured to the layer by means of rivets extending through and upset in the several rivet holes hereinbefore specified.

In testimony whereof I affix my signature, 90 in the presence of two witnesses.

CURTIS JOHNSON.

Witnesses:

E. A. JOHNSON,
A. RAY MAXWELL.
